UNITED STATES PATENT OFFICE.

JOSEPH A. WILLIAMS, OF CLEVELAND, OHIO, ASSIGNOR TO THE WILLIAMS ABBOTT ELECTRIC COMPANY, OF SAME PLACE.

MAGNETO-ELECTRIC GENERATOR.

SPECIFICATION forming part of Letters Patent No. 591,365, dated October 5, 1897.

Application filed May 3, 1897. Serial No. 634,865. (No model.)

To all whom it may concern:

Be it known that I, JOSEPH A. WILLIAMS, a citizen of the United States, residing at Cleveland, in the county of Cuyahoga and State of Ohio, have invented certain new and useful Improvements in Magneto-Electric Generators, of which the following is a specification.

This invention relates to magneto-electric generators, and has for its object economy of construction and greater efficiency of electrical generation; and it consists in the details of construction and combination of parts substantially as hereinafter described, and pointed out in the claims.

15 In the accompanying drawings, Figure 1 is a vertical section of my new generator. Fig. 2 is an end view of the same. Fig. 3 is a detached view of one of my new pole-pieces. Fig. 4 is a view of the flattened bolt.

20 In this generator there are three special features of improvement: first, a greater effective length of permanent magnets obtained by the use of a new and novel pole-piece; second, the obtaining of a greater width of permanent magnets in a given space by the use of flattened bolts for the purpose of binding them together; third, a simple and efficient electrical shunt for the purpose of short-circuiting the windings of the armature when 25 out of action, in combination with the supporting-pieces that hold the brush. These ends are obtained substantially by the constructions and combinations as follows:

30 A A are end plates of non-magnetic metal, having the bearings for the armature and driving shafts. The side edges are curved to conform to the armature-circle, and have curved flanges a a, to which the pole-plates are secured; also have radial ribs a', which 35 have bores leading from the outside to the journal-bearings for the purpose of injecting oil for lubricating the armature-bearings.

35 B B are pole-plates, which are of novel construction, consisting of sheet metal cut and stamped in the form shown in Fig. 3. The lower edges of said plates are bent and folded upward with square corners, providing a narrow bottom edge. The upward fold b is cut or slotted vertically and the cut edges of the 40 two side-slotted portions are bent outward at right angles to the plate. These are to form

seats for the ends of the permanent magnets. The pole-plates are fastened to the end plates A A by screws c c.

The greater effective length of permanent 55 magnets is obtained by changing the point of contact of the pole-plates with the magnets from the usual place, which has heretofore been at or about a line horizontally tangent with the top of the armature-circle, to a position horizontally bisecting the armature-circle; also, by turning up and flanging the lower part of the pole-plates a better and more efficient magnetic contact is formed in the space between the line horizontally bisecting the armature-circle and the bottom 60 ends of the magnets, and the space on the permanent magnets between the flattened clamping-bolts and the horizontal center line of the armature-circle is gained for effective 65 use in this machine.

It is well known in magnetism that at a point where a permanent magnet is short-circuited or its free ends closed by a magnetic material the lines of force traversing the 70 armature or magnetic material are greater toward the ends and are less on a nearer approach to the neutral axis of the magnet. It will therefore be seen that by attaching the pole-plates at or near the ends of the magnets 75 and that by the use of the flattened bolts and the peculiar construction of my pole-plates I am enabled to obtain a much better and more efficient contact, not only a greater efficient length, but a greater width of magnet-steel, 80 thereby covering as near as possible the external surface of the rotative armature.

C C C are the permanent magnets, which are of greater width than ordinarily used, for the purpose of placing them as close together 85 as possible, leaving but a narrow space between them.

D D are binding-bolts, made flat to adapt them to fit between said magnets without reducing their strength, for with these bolts the 90 magnets are firmly drawn into their seats in the pole-plates and thus make a close and complete contact of the magnets with the pole-plates.

E is a driving-shaft journaled in the bearings e e of the end plates A A, carrying the driving gear-wheel G, which meshes with the 95 100

pinion on the armature-shaft. On said shaft is provided an automatic shunt, described as follows:

H is a disk and sleeve loosely placed on the shaft E, having a slot in which a pin on the shaft plays. This will allow the sleeve and disk to have movement longitudinally while it revolves with the shaft. A spring s on said sleeve, bearing against the disk, and a collar r on the shaft force the disk away from the collar. E' is a cylinder covering the shaft from the said disk H through the bearing to the driving-wheel G, which is fastened firmly on the cylinder. In the end of the cylinder is made a notch g, fitting over a projection h on the disk.

J is an arm attached to the end plate A for contacting with the disk. It is fixed by screws jj through insulating fiber pieces kk, placed on each side of an opening through the plate.

L is a strip of metal held by the screws jj on the outside of the end plate A, which extends down to and contacts with a pin l in the end of the armature-shaft. The pin l is connected with the wire winding of the armature.

The operation as follows: When the machine is at rest, the disk II is in contact with the arm J, and a short circuit is thereby made.

When the machine is put into operation, the turning of the crank turns the driving-shaft in the cylinder E'. This turns the disk and sleeve II, causing the riding of the projection h out of the notch g, forcing the disk and

compressing the spring s toward the collar

and away from the arm J. This opens the short circuit. Now the continued rotations of the shaft E carry the wheel G with it by the binding of the cylinder on the shaft, and the armature is then revolved.

40

Having described my invention, I claim—

1. In a magneto-electric generator, the pole-piece consisting of a plate cut, stamped and formed with the lower edge slotted, folded upward, and with the outward bends forming 45 seats for the permanent magnets, substantially as described.

2. In a magneto-electric generator, the combination with the magnets C C C, of the flattened bolts D D, substantially as and for the 50 purpose set forth.

3. In a magneto-electric generator, the combination with the driving-shaft E of the cylinder E', notch g in end of said cylinder, sleeve and disk II, projection h on said disk 55 engaging with said notch, spring s on the sleeve H, and collar r on the shaft E, the arm J attached to plate A by insulating-pieces kk, and contacting with the disk II, and the strip L, attached on outside of plate A, by the 60 screws jj and contacting with the pin l in the armature-shaft, the arrangement being such that when the machine is at rest a short circuit is made through the arm J and disk II as and for the purpose specified.

JOSEPH A. WILLIAMS.
